UNITED STATES PATENT OFFICE.

ALEX MARCUS, OF BROOKLYN, NEW YORK.

DESIGN FOR A POWDER-PUFF.

53,398.

Specification for Design.

Patented June 3, 1919.

Application filed January 25, 1919. Serial No. 273,180. Term of patent 14 years.

To all whom it may concern:

Be it known that I, ALEX MARCUS, a citizen of the United States, residing at Brooklyn, in the county of Kings and State of New York, have invented a new, original, and ornamental Design for a Powder-Puff, of which the following is a specification, reference being had to the accompanying drawings, forming a part thereof, and in which—

Figure 1 is a top view, and

Copies of this patent may be obtained for five cents each, by addressing the "Commissioner of Patents, Washington, D. C."

Fig. 2 an edge view of a powder puff embodying my design.

I claim:

The ornamental design for a powder puff, as shown.

ALEX MARCUS.
